(57) CLAIM

The ornamental design for a floor tile as shown and described.

DESCRIPTION

This patent application contains at least one drawing/photograph executed in color. Copies of any issued patent based on this application with color drawing(s)/photograph(s) will be provided by the Office upon request and payment of the necessary fee.

FIG. 1 is a top plan view of a floor tile showing a first embodiment of our new design; and,

FIG. 2 is a top plan view of a floor tile showing a second embodiment of our new design.

The grayscale photographic area of FIG. 1 and the color photographic area of FIG. 2 are claimed. The grayscale contrast in FIG. 1 represents a contrast in appearance only and does not represent any particular color. The colors in FIG. 2 are claimed.

1 Claim, 4 Drawing Sheets
(2 of 4 Drawing Sheet(s) Filed in Color)
